Patented Feb. 1, 1916.

UNITED STATES PATENT OFFICE.

HANS STAMM, OF ST. GALLEN, SWITZERLAND, ASSIGNOR TO THE FIRM OF ADOLPH SAURER, OF ARBON, SWITZERLAND.

CARTRIDGE-CASE EXTRACTOR FOR FIREARMS.

1,170,014.

Specification of Letters Patent.

Patented Feb. 1, 1916.

Application filed May 27, 1915. Serial No. 30,774.

To all whom it may concern:

Be it known that I, HANS STAMM, a citizen of the Republic of Switzerland, residing at St. Gallen, Switzerland, have invented new and useful Improvements in Cartridge-Case Extractors for Firearms; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention has for its object to provide an improved method of mounting the cartridge case extractor in straight-pull breech actions of rifles of the type, wherein the breech action consists of a rotatable breech bolt provided with locking nibs and of a bolt actuating sleeve mounted to slide longitudinally on the said bolt; both parts, namely, the breech bolt and the sleeve engaging each other by means of helical parts 25 and helical grooves, while the sleeve is slipped from the front over the bolt.

In breech actions of the above specified type, the extractor has hitherto been mounted or rather embedded in the breech bolt in such a manner as to allow the breech bolt in its movement to slide over the extractor. That method of mounting the extractor has, however, the drawback that the breech bolt is weakened at its front end to such a great extent that the extractor is of weak construction, and that the removal of the extractor can only be effected with difficulty, that is to say, only with a great exertion of force.

40 Now those drawbacks are avoided by the present invention according to which instead of mounting the extractor in the breech bolt as hitherto, the extractor is mounted in the breech bolt actuating sleeve 45 and in such a manner that it is fixed relatively to the breech bolt so that, although it cannot rotate, it will move longitudinally with the breech bolt, and will be guided along the bolt actuating sleeve in the sliding 50 movement of the latter.

The extractor may be arranged to move in a longitudinal groove in a guide ledge of the bolt actuating sleeve, and engage by means of a lug in an annular segment-shaped groove in the breech bolt. Further

in straight-pull breech actions of the type wherein the bolt actuating sleeve is slipped from the front over the breech bolt, the extractor may serve to limit the forward movement of the bolt actuating sleeve when the breech action has been removed from the breech frame.

The improved method of mounting the extractor compared with the method hitherto in use, has the advantage that the extractor can be made strong enough without weakening the breech bolt, and can also be easily removed.

One form of this invention is illustrated by way of example in the accompanying drawings in which:

Figure 1 is a horizontal longitudinal section of a straight pull breech action of the specified type, showing the breech action in its unlocked and drawn back position in a 75 military rifle. Fig. 2 is a side elevation of a part of the breech action. Figs. 3 and 4 are sections respectively on lines A—B and C—D of Fig. 2. Fig. 5 is a front end elevation of the breech bolt. Figs. 6 and 7 are 80 respectively a side elevation and a plan of the extractor shown separately; and Fig. 8 shows the breech action in its locked condition.

As shown, the breech action consists of the 85 rotary breech bolt 1 which is provided with locking nibs 2 at its rear end, and of the bolt actuating sleeve 3, which is slipped from the front on to the bolt 1 and is slideable in a straight line along the latter. The 90 sleeve 3 is provided with a handle 4 and two side guide ledges 5 by means of which latter the sleeve is guided in horizontal guide grooves 6 in the breech frame 7 of the rifle (Fig. 8).

95 The sleeve 3 engages by means of helical pieces 8 in helical grooves 9 in the bolt (Fig. 1), and has sufficient play on the bolt lengthwise of the latter, when the sleeve is slid along it, to allow of imparting to the bolt 100 by means of the helical pieces and helical grooves a quarter turn in each direction which is requisite for locking and unlocking the breech action. In these latter operations the locking nibs 2, of the breech bolt 105 enter or leave recesses (not shown) which are formed in the rear part of the breech frame, and which communicate with the guide grooves 6. In the locked condition of the breech action the nibs 2 lie in a vertical 110

plane (Fig. 8), whereas in its unlocked condition, the nibs 2 lie in a horizontal plane (Fig. 1).

The extractor 10 (Figs. 6 and 7) is mounted on the outer side in the right hand guide ledge 5 of the sleeve 3 (Figs. 1 and 8); it is guided by means of its rear portion (of dovetail shape in cross section) in a correspondingly shaped guide groove 5' in the said ledge (Fig. 3). It is fixed against longitudinal movement relatively to the bolt 1, inasmuch as it engages by means of a lug 11 in an annular segmental groove 12 in the bolt (Figs. 1 and 4). This groove is so dimensioned that the bolt 1 is free to make a quarter turn in each direction in the locking and unlocking operations, the extractor 10 sliding in the guide groove 5' in the sleeve. The extractor therefore shares the longitudinal movements of the bolt during the pulling back and pushing forward of the breech action in the loading operation.

The sleeve 3 has in its front part a notch 3' for the forward broader end of the extractor which carries the extracting claw 13. This claw projects beyond the forward end of the breech bolt, and when a cartridge is pushed into the cartridge chamber, it springs out in the usual manner and engages the rim of the cartridge (Fig. 8). When the breech action is pulled back, the empty cartridge case is extracted by the extractor. The extractor has a thinner central portion 10' which allows the forward portion 35 of the extractor to spring out.

When it is desired to remove the extractor its forward portion is sprung outward until the lug 11 has moved out of the groove 12; then the extractor is drawn out of the groove 5' in the sleeve, and then the sleeve itself can be slipped forwardly off the bolt.

Having now particularly described and ascertained the nature of my said invention and in what manner the same is to be performed, I declare that what I claim is:

1. In a straight-pull breech action for rifles, a rotatable breech-bolt provided with locking nibs at its rear end, a breech bolt actuating sleeve slidable longitudinally on the bolt, said bolt and sleeve engaging each other by corresponding helical parts, the sleeve being slipped from the front over the bolt, a cartridge case extractor mounted at the outside of a guide ledge of the sleeve and having a fixed longitudinal position relatively to the breech bolt but not rotating therewith, said extractor being guided along the bolt actuating sleeve by the sliding movement of the latter, the front end of the extractor forming a stop to prevent the sleeve from falling off when the breech action has been removed from the breech frame.

2. In a straight-pull breech action for rifles, a rotatable breech bolt provided with

locking nibs, a breech bolt actuating sleeve slidable longitudinally on the said bolt and guided in the breech frame by means of lateral guide ledges, said bolt and sleeve engaging each other by corresponding helical parts, the sleeve being slipped from the front over the bolt, a cartridge case extractor slidable in a dove-tail longitudinal groove at the outside of one of the said lateral guide ledges of the sleeve and having a fixed longitudinal position relatively to the breech bolt, but not rotating therewith, said extractor being guided along the bolt actuating sleeve in said groove by the sliding movement of the sleeve.

3. In a straight-pull breech action for rifles, a rotatable breech bolt provided with locking nibs, a breech bolt actuating sleeve slidable longitudinally on said bolt and guided in the breech frame by means of lateral guide ledges, said bolt and sleeve engaging each other by means of corresponding helical parts, the sleeve being slipped from the front over the bolt, a cartridge case extractor slidable in a dove-tail longitudinal groove at the outside of one of said lateral guide ledges of the sleeve and engaging by means of a lug on its front end into an annular segmental groove in the breech bolt, said extractor having a fixed longitudinal position relatively to the breech bolt but not rotating therewith, and guided along the bolt actuating sleeve in the longitudinal groove by the sliding movement of the sleeve.

4. In a straight-pull breech action for rifles, a rotatable breech bolt provided with locking nibs, a breech bolt actuating sleeve slidable longitudinally on said bolt and guided in the breech frame by means of lateral guide ledges, said breech bolt and sleeve engaging each other by corresponding helical parts, the sleeve being slipped from the front over the bolt, a cartridge case extractor slidable in a longitudinal groove at the outside of one of said lateral guide ledges of the sleeve and engaging by means of a lug on its front end into an annular segmental groove in the breech bolt, said extractor having a fixed longitudinal position relatively to the breech bolt, but not rotating therewith, and being guided along the bolt actuating sleeve in the said longitudinal groove by the sliding movement of the sleeve, and means to limit the forward movement of the bolt actuating sleeve when the breech action has been removed from the breech frame.

5. In a straight-pull breech action for rifles, a rotatable breech bolt provided with locking nibs, a breech bolt actuating sleeve slidable longitudinally on said bolt and guided in the breech frame by means of lateral guide ledges, said bolt and sleeve engaging each other by corresponding heli-

cal parts, the sleeve being slipped from the front over the bolt, a cartridge case extractor slidable in a longitudinal groove at the outside of one of said lateral guide 5 ledges of the sleeve and a lug on its front end engaging an annular segmental groove in the breech bolt, said extractor having a fixed longitudinal position relatively to the breech bolt, but not rotating 10 therewith, and being guided along the bolt actuating sleeve in said longitudinal groove by the sliding movement of the sleeve, the front portion of the extractor carrying the lug serving as a stop for limiting the forward movement of the bolt actuating sleeve 15 when the breech action has been removed from the breech frame.

In testimony that I claim the foregoing as my invention, I have signed my name in presence of two subscribing witnesses.

HANS STAMM.
